UNITED STATES PATENT OFFICE.

HERBERT H. BONNELL, OF DENVER, COLORADO.

FLOTATION APPARATUS.

1,399,539.

Specification of Letters Patent. Patented Dec. 6, 1921.

Application filed April 3, 1918. Serial No. 226,386.

To all whom it may concern:

Be it known that I, HERBERT H. BONNELL, a citizen of the United States, residing at the city and county of Denver and State of Colorado, have invented certain new and useful Improvements in Flotation Apparatus; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to the separation of mineral values by what is known as the flotation process.

The object of the invention is to obtain the separation readily and completely, and with 20 a simple apparatus.

Briefly the invention consists in a machine and process by which the pulp mixed with oil is introduced into the first of a plurality of compartments, carried up through a passage by an airlift, or other suitable means, overflowed onto a smooth or preferably riffled aeration apron from which it flows back partly into the first compartment and partly into the adjacent compartment. The 25 scum or, froth rises to the surface as the pulp flows over the apron, is in a sense dried thereon and floats better after flowing back into the tank, from which it is skimmed off into a launder.

30 Referring to the accompanying drawings: Figure 1 is a side elevation of the apparatus.

Fig. 2 is a front view as indicated by the line 2—2, of Fig. 1.

40 Fig. 3 is a longitudinal section taken on the line 3—3 of Fig. 1.

Fig. 4 is a plan view as indicated by line 4—4, of Fig. 1.

45 Fig. 5 is an elevation of a slightly modified form.

Fig. 6 shows partly in section a modified form of pulp-elevating mechanism.

50 Fig. 7 is an exploded perspective showing the parts of the valve controlling the tailings discharge.

A plurality of compartments are used, there being shown in the drawing a receiving compartment 12, an intermediate compartment 13, and a tailings discharge compartment 14. Each compartment is tapered toward the bottom thereof both laterally and

longitudinally and in such manner that the tops of the dividing walls 15 slope upwardly from the rear of the machine to the front of the machine as indicated in dotted lines 60 in Fig. 1, the uppermost part 16 being horizontal and extending slightly above the front wall, as shown in Fig. 2, whereby the forward part of each compartment is separated from the adjacent compartment. 65

A pulp-feed pipe 17 having a funnel-shaped top enters the receiving compartment 12 at a point below the normal liquid level indicated in Fig. 1 by the dashed line 18.

Along the back wall of each compartment 70 a pipe 19 extends from the bottom to the top and opens into a hood 20 which extends across the back of the entire machine and has its forward side open. An apron 21 also extends the full length of the machine, 75 and from the back of the hood 20 forwardly about half the width of the machine or a little more, the rear of the apron being apertured to register with pipes 19. This apron is preferably provided with riffles 22, and 80 the forward end may be supported by adjustable braces 23 for varying the inclination of the apron, the rear end being hinged or otherwise suitably supported.

For each pipe 19 an airlift is provided 85 which comprises a nozzle 24 extending through the bottom of the compartment into the lower part of the pipe, and communicating with a compressed air pipe 25. Each nozzle is controlled by a valve 26, and the 90 pipe 25 by a valve 27.

At the forward edge of the machine a skimmer 30 is journaled in arms 31 and skims off the froth or scum into launder 32. The blades 33 of the skimmer are crenelated 95 at 34 to fit about the upstanding edges 16 of the partitions 15. The skimmer may be rotated by any means such as a belt 35 and motor 36.

The tailings discharge is from the compartment 14 through a pipe 40 and is controlled by a valve A whose parts are shown in Fig. 7. This valve is operated by arms 41 and 42 which are pivoted together, arm 42 being slotted and engaging a guiding pin 100 or screw 43. The movement of the arms is controlled by a float 44 secured to the upper end of arm 42.

The valve A is composed of an inner cylindrical member 50 and an outer cylindrical 110 member 51 which fits over the cylinder 50 and to which the arm 41 is secured. The

outer ends of these cylinders are provided with apertured walls 52 and 53, the apertures being adapted to register or to be arranged out of registry and thus control the flow 5 of liquid therethrough. The cylinders are pivotally secured in operative relation by a screw bolt which passes through perforations in the center of the walls 52 and 53.

In Fig. 5 a slight modification of the tank 10 structure is shown. Here the tank is only about half as wide as the tank of Fig. 1, this structure being practicable for the reason that only the front half of the form of Fig. 1 is actually used. In this modification the airlift pipe 19' extends outside of the tank to hood 20', the forward edge of the apron 21' resting on the top of the rear wall of the tank.

In Fig. 6, an endless bucket conveyer 60 20 is shown as a substitute for the air lift of the other form, this conveyer working in a vertical chamber 61, the bottom of which is connected with the bottom of the tank by a passage 62. The conveyer may be operated 25 by such means as a motor 63, and the discharge from the buckets is through a spout 64 in the top of the chamber 61 onto the apron (not shown).

In the operation of the machine the pulp 30 mixed with oil is fed through pipe 17, where slight mixing and aeration takes place, into the receiving compartment 12 and is forced by the airlift 24 up through pipe 19, where it is thoroughly mixed with 35 air, into hood 20, whence it flows down over apron 21 in a thin stream. Thus the mineral-oil-air bubbles, have an opportunity to rise freely and quickly to the surface through the thin stream of pulp without 40 resistance or obstruction, instead of having to rise through a great body of pulp as heretofore. The riffles 22 form a series of cascades which aid in aerating the pulp in addition to the aeration obtained by the 45 airlift. At the same time the froth rises to the surface and is in a sense dried. When the pulp falls off of the apron, part of the 50 froth or scum containing the mineral and oil will be carried below the surface, but due to its buoyancy will quickly rise again. The froth will pass toward the launder 32 and be fed into it by the skimmer 30, while the gangue will settle.

As the pulp flows over the apron, part 55 of it will pass back into the compartment 12, while the rest of it will flow into the next compartment 13. In each case it will be carried up to the hood 20 and again be flowed over apron 21. Eventually the gangue reaches the last compartment 14 from 60 which it is discharged through pipe 40, the discharge being regulated by valve A and float-control 44.

A smooth apron may be used as shown 65 in Fig. 5 although the cascade effect and

accompanying results are not obtained as where riffles are used.

What I claim as new is:

1. In flotation apparatus, the combination with a plurality of adjacent compartments, 70 of an aerating apron extending across all of said compartments, and a lift extending from the lower portion of each compartment to said apron to flow the pulp onto the apron, said apron permitting the pulp elevated by each lift to spread and flow partly back to the corresponding compartment and partly to the adjacent compartment. 75

2. In flotation apparatus, the combination with a plurality of adjacent compartments, 80 of an aerating apron extending across all of said compartments, an airlift extending from the lower portion of each compartment to said apron to flow the pulp onto the apron, and a hood at the top of said 85 airlifts to direct the pulp onto the apron, said apron permitting the pulp elevated by each lift to spread and flow partly back to the corresponding compartment and partly to the adjacent compartment. 90

3. A flotation apparatus, a plurality of compartments, a partition between said compartments, the forward walls of said compartments being lower than the other walls to establish an overflow, the forward 95 upper edge of said partition being higher than said forward walls to separate the forward portions of adjacent compartments, the top of the rear portion of the partition sloping rearwardly to a point below the 100 overflow level.

4. A flotation apparatus, a plurality of compartments, a partition between adjacent compartments, the forward walls of said compartments being lower than the other walls to establish an overflow, the forward 105 upper edge of said partition being higher than said forward walls to separate the forward portions of adjacent compartments, the top of the rear portion of the partition sloping rearwardly to a point below the overflow level, and a skimmer located at the forward portion of the device and having skimming blades which are crenelated to fit said uppermost partition edge. 110

5. Flotation apparatus comprising a plurality of compartments, partitions between said compartments, the forward walls of said compartments being lower than the other walls to establish an overflow, the forward 115 upper edge of said partitions being higher than the forward walls to separate the forward portions of adjacent compartments, the rear portion of the partitions sloping rearwardly to points below the overflow level, pulp elevating means extending upwardly from the bottom of each compartment, an apron sloping downwardly from the top of the elevating means and over each of said compartments onto which 120

apron the pulp may be flowed from said elevating means and from which it may flow back into the compartments, whereby the pulp from one elevating means will flow back partly into the compartment whence it comes, and partly into the next succeeding compartment.

6. A flotation apparatus, comprising a plurality of compartments, a partition between the adjacent compartments, the forward walls of said compartment being lower

than the other walls to establish a froth overflow, means to establish a pulp level, the forward upper edge of said partition extending above said pulp level to separate 15 the forward portions of adjacent compartments, the top of the rear portion of the partition extending below the pulp level.

In testimony whereof I affix my signature.

HERBERT H. BONNELL.
